UNITED STATES PATENT OFFICE.

JEAN LOUIS MAZOYER, OF NEW YORK, N. Y.

IRONING-MACHINE.

SPECIFICATION forming part of Letters Patent No. 389,971, dated September 25, 1888.

Application filed July 25, 1887. Serial No. 245,263. (No model.)

To all whom it may concern:

Be it known that I, JEAN LOUIS MAZOYER, a citizen of France, and at present residing in the city, county, and State of New York, have 5 invented a new and Improved Ironing-Machine, of which the following is a full, clear, and exact description.

My invention relates to that class of ironing-machines in which a heated polishing-cylinder moves upon the articles to be ironed and polished, said articles being held in position 10 on a bed or table to receive the action of said cylinder.

The invention consists in the construction 15 and arrangement of certain parts and details and combinations of the same, as will be fully described hereinafter, and then pointed out in the claims.

Reference is to be had to the accompanying 20 drawings, forming a part of this specification, in which similar letters of reference indicate corresponding parts in all the figures.

Figure 1 is a side elevation of my improvement. Fig. 2 is a plan view of the same. Fig. 25 3 is a vertical cross-section of the same on the line $x-x$ of Fig. 1, looking in the direction of the arrow x' . Fig. 4 is a front elevation of the polishing-cylinder support, with the polishing-cylinder partly in section. Fig. 5 is a side 30 elevation of the mechanism for rotating the polishing-cylinder when its support is not oscillating. Fig. 6 is a side elevation of the device for operating the mechanism shown in Fig. 5. Fig. 7 is a plan view of the supporting-arm for the ironing-table. Fig. 8 is a side 35 elevation of the shifting mechanism. Fig. 9 is a vertical cross-section of the ironing-table and its support on the line $y-y$ of Fig. 1. Fig. 10 is a detailed view of the catch for holding 40 the shifting-lever in position, and Figs. 11 and 12 are detail views of the device for locking the roller to which the article to be ironed is secured.

On a suitably-constructed frame, A, is mounted 45 the driving-shaft B, carrying the fast and loose pulleys C and C', respectively connected, in the usual manner, by a belt with machinery for rotating said driving-shaft B. On the driving-shaft B is secured a pinion, D, which 50 meshes into the gear-wheel E, secured to the

crank-shaft F, mounted in suitable bearings on the main frame A. In the middle of the shaft F is formed a crank-arm, F', connected with the lever G, fulcrumed on the shaft G', secured to the main frame A, near its bottom. 55

In the upper forked end of the lever G is held a shaft, G², on which is fulcrumed the middle part of the lever H, also provided at its rear end with a shaft, H', secured in the slotted forked end I' of the vertical arm I, 60 fulcrumed at I² on the main frame A. The shaft H' is held in place by the set-screws J and J' screwing in said arm I, so that the shaft H' may be adjusted vertically in the slotted end of the arm I. The front end of the lever 65 H supports the platform H², on which the ironing-table K is held adjustably by means of the screws K', which screw into said platform H², and by the set-screws K² and K³ for adjusting the position of said table K in relation to the platform H². 70

On the upper surface of the ironing-table K is held the polishing-cylinder L, provided with the trunnions L', mounted to rotate in the upper ends of the forked lever N, fulcrumed 75 at its lower end on the shaft N', held on the main frame A. The lever N is pivotally connected by the links O with the crank-arms P, formed on the outer ends of the crank-shaft F, said crank-arms P standing diametrically opposite the crank-arm F', as illustrated in Fig. 3. 80

On one of the trunnions L' of the polishing-cylinder L is secured a ratchet-wheel, L², with which engages a pawl, L³, pivoted on the bearing of said trunnion L'. This pawl L³ permits 85 the polishing-cylinder L to rotate when moving toward the front end of the machine, but prevents a rotary motion when moving backward, so that the polishing-cylinder L glides over the article to be ironed. Into one of the 90 hollow trunnions L' of the polishing-cylinder L passes a pipe, Q, which extends into the cylinder L, and is perforated at its inner end, as illustrated in Fig. 4. To the outer end of the pipe Q leads a gas-pipe, Q', and the two 95 air-pipes, Q², so as to lead a mixture of gas and air into the interior of the cylinder L, in which said mixture is burned by igniting it in the usual manner, so that the polishing-cylinder L may be heated. 100

On the other trunnion L' of the polishing-cylinder L , which may be either hollow or solid, is secured a ratchet-wheel, R , which engages a pawl, R' , pivoted on one end of the bell-crank lever R^2 , mounted loosely on the reduced end of the trunnion L' , as shown in Fig. 5. The other arm of the bell-crank lever R^2 connects by means of the link R^3 with the bell-crank lever R' , fulcrumed on the main frame 5 A, and connected by the rod R^5 with the eccentric R^6 , mounted on a shaft, R^7 , having its bearings in the main frame A at the rear of the machine. On the shaft R^7 is secured a gear-wheel, R^8 , which meshes into a pinion, C^2 , 10 formed on the hub C^2 of the loose pulley C' , rotating loosely on the main shaft B.

On the lever H is held a device for fastening the articles to be ironed on the table K, and this device consists, principally, of an 15 arm, S, fulcrumed by its rear end at S' to said lever H, and provided at its front end with a flat holder, S^2 , fitting over the rear end of the table K, as illustrated in Figs. 1 and 2. On top of the arm S operates a cam, S^3 , provided 20 with a handle, S^4 , and fulcrumed on a bracket secured to the lever H. A spring, S^5 , is secured to the same bracket and presses against the under side of the arm S, so that when the handle S^4 is pushed backward, whereby its cam 25 S^3 disengages the arm S, then the spring S^5 causes an upward swinging motion of the arm S, so that its front end, S^2 , is disengaged from the table K.

The cloth T is usually placed on top of the 30 table K and held by one end under the free end of the arm S, and by its other end is wound around a roller, T' , provided with pins, so as to hold said cloth stretched over the table K. In front of said roller T' is held a 35 second roller, T^2 , for fastening the end of the article to be ironed. The roller T^2 is provided with a series of pins, and to its outer end is fitted the handle T^3 . The handle T^3 is provided with the pins T^4 , adapted to engage apertures formed in one of the brackets, K^4 , in 40 which the said roller T^2 is journaled. To permit the pins of the handle to be engaged or disengaged from the apertures in the bracket, the shank of the handle fits in a socket in the 45 end of the roller, and is provided with a pin, t , projecting into a slot, t^2 , so that handle will be locked to the roller, but will be free to slide back and forth in the socket of the roller, as clearly shown in Fig. 12. By this construction, 50 by pulling the handle T^3 outward until the pins T^4 are disengaged from the apertures of the bracket, the roller T^2 can be turned by the handle so as to stretch the article to be ironed tightly over the table K, after which the handle T^3 is pushed back, when the pins T^4 will enter other apertures in the bracket K^4 , and thus lock the roller T^2 in the position to 55 which it has been turned.

The shifting-bar U, operating the belt connected with the fast and loose pulleys C and C', is connected with a bell-crank lever, U', fulcrumed on a bracket, U^2 , secured to the main

frame A. The bell crank lever U' is connected by the link U^3 with an extension, U^4 , projecting from the treadle-arm U^5 , secured at U^6 on the main frame A. The treadle-arm U^5 projects from the front end of the machine and carries a treadle-board, U^7 , for the operator's foot. A spring, U^8 , is connected with one end of the treadle-lever U^5 , and at its other end 70 with the main frame A, and has the tendency with the main frame A, and has the tendency 75 to pull the treadle-lever U^5 upward, so that the shifting-bar U holds the driving-belt on the loose pulley C', so that the machine does not run.

The treadle-lever U^5 may be locked in position when in its lowest place by the spring-catch V, having the shoulder V' engaging one edge of the treadle-board U^7 , as illustrated in Fig. 8. A spring, V^2 , presses against said 85 catch V, so as to hold the same engaged with the treadle-board U^7 , and said catch is fulcrumed on a bracket, V^3 , extending from the main frame A.

The operation is as follows: The article to be ironed is placed on the ironing-table K, and fastened by the free end of the arm S and by the pin-roller T', as above described. The operator then presses his foot on the treadle-board U^7 , whereby the fork of the shifting-bar U is 90 moved endwise, so that the driving-belt passes on the fast driving-pulley C, whereby the crank-shaft F is set in motion. The rotary motion of the main shaft B is transmitted by the pinion D and the gear-wheel E to the crank-shaft 95 F, which, by its crank-arm F' and the lever G, imparts an oscillating motion to the table-lever H, thereby oscillating the table K. At the same time the crank-arms P of the crank-shaft F impart an oscillating motion by the 100 links O to the lever N, so that the polishing-cylinder L swings over the ironing-table K, but in an opposite direction to the latter, on account of the crank-arms P standing diametrically opposite to the crank-arm F. The polishing-cylinder L, on moving toward the front 105 of the machine, is rotated by coming in contact with the article to be ironed, and moving toward the rear with the table K; but when the latter oscillates toward the front 110 and the polishing-cylinder commences its return movement the latter is prevented from rotating by the pawl L' engaging the ratchet-wheel L^2 , so that the said polishing-cylinder L glides over the article to be ironed. 115 It will thus be seen that the article is ironed by a rotary movement of the polishing-cylinder L, and by a gliding movement of the same at the respective forward and backward movement of the said polishing-cylinder. 120 The table K can be adjusted by the screws K' and the set-screws K² and K³, so that the polishing-cylinder L will pass evenly over the article to be ironed and held on the table K. The 125 lever H, supporting the table K, can also be 130 adjusted up and down at its rear end by the set-screws J and J', held in the pivoted arm I, so as to raise or lower the table K. The articles to be ironed and hanging over the table

K at either side are supported by the trough or chute H³, held below said table, and moving with the same on account of being fastened to the lever H. When the operator presses the 5 treadle-board U⁷ downward, as before described, then the spring-catch V engages the edge of said treadle-board U⁷, thus locking the latter in position, and thereby holding the fork of the shifting-bar U over the fast pulley C. When the operator desires to stop the 10 machine, he presses the spring-catch V toward the rear with his foot, disengaging the same from the treadle-board U⁷, so that the spring U⁸ pulls the treadle-lever U⁵ upward, whereby 15 the shifting-bar U is moved inward and the driving-belt is passed on the loose pulley C'. The oscillating movements of the table K and the lever N, supporting the polishing-cylinder L, have ceased; but the polishing-cylinder 20 is kept rotating in its bearings by the rotation of the loose pulley C', which, by its pinion C³, formed on its hub C², imparts a rotary motion to the gear-wheel R⁸, thereby rotating the shaft R⁷. The latter sets the eccentric R⁶ in motion, 25 whereby a rocking motion is given to the bell-crank lever R⁴, and this rocking motion is transmitted by the link R³ to the bell-crank lever R², which, by its pawl R', turns the ratchet-wheel R, secured to one of the trun-

nions L' of the polishing-cylinder L, so that the 30 latter is rotated.

Having thus described my invention, what I claim as new, and desire to secure by Letters Patent, is—

1. In an ironing-machine, the combination, 35 with a shaft, of a polishing-cylinder, a lever on which said polishing-cylinder is mounted, and which lever is connected with a crank-arm on said shaft, an adjustable ironing-table held below said polishing-cylinder, and an adjustable lever supporting said ironing-table at one end and connected with the crank-arm on said shaft, substantially as shown and described. 40

2. In an ironing-machine, the combination, 45 with a crank-shaft and a lever pivoted at its lower end and connected at about the center of its length to the crank of the said shaft, of the lever H, provided with shaft H', the ironing-board K, secured to one end of the said lever, the arm I, pivoted at its lower end, and 50 having its upper end slotted to receive the shaft H', and the screws J J', for adjusting the shaft H' in the slot of the arm I, substantially as herein shown and described.

JEAN LOUIS MAZOYER.
